(57) **CLAIM**

What is claimed is the ornamental design for a book that includes soil from predetermined places, as shown and described.

DESCRIPTION

FIG. 1 is a perspective view while in an open position for a book that includes soil from predetermined places showing my new design.

FIG. 2 is a front elevational view thereof while in an open position. The back elevational view thereof while in the open position contains no ornamentality and is therefore omitted. FIG. 3 is a bottom plan view thereof while in an open position. The opposite side being a mirror image thereof.

FIG. 4 is a front elevational view thereof while in a closed position. The front elevational view thereof while in the closed position contains no ornamentality and is shown to identify cross sectional lines 5-5 and 6-6 thereof. The back elevational view thereof in the closed position contains no ornamentality and is therefore omitted.

FIG. 5 is a cross sectional view thereof taken on line 5-5 of FIG. 4.

FIG. 6 is a cross sectional view thereof taken on line 6-6 of FIG. 4.

FIG. 7 is a right elevational view thereof while in the open position; and,

FIG. 8 is a left elevational view thereof while in the open position.
